PANEL.

No. 16,462.

Patented Jan. 12, 1886.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,462, dated January 12, 1886.

Application filed November 13, 1885. Serial No. 182,770. Term of patent 7 years.

To all whom it may concern:

Be it known that I, FREDERICK MANKEY, of Williamsport, Lycoming county, Pennsylvania, have invented and produced a new and 5 original Design for Panels, of which the following is a specification, reference being had to the accompanying photograph, forming part hereof.

My design consists in the rectangular frusto-pyramidal elevation A. Parallel to each side of said elevation A is an elongated pyramidal elevation, as D E F G. Between said elevations D E F G, and at the corners of the panel, are smaller square pyramidal elevations H I 15 J K. Between the said elevations are channels L M and N O.

Upon the face of the elevation A appear four lenticular-shaped scores or indentations, P Q R S. These radiate from a central annular

depression, T, in which is a convex circular 20 elevation, U.

A different grain-marking may appear upon the inclined sides of the elevation A and upon the elevations D E F G H I J K from that which appears upon the flat face of said elevation A. 25

I claim—

The design for a panel, substantially as herein shown and described, which consists of the frusto-pyramidal elevation A, the pyramidal 30 elevations D E F G H I J K, and the channels L M N O, and on the face of elevation A the lenticular scores or channels P Q R S, annular depression T, and convex elevation U.

FREDERICK MANKEY.
